UNITED STATES PATENT OFFICE.

ALFRED W. COCHRAN, OF NEW YORK, N. Y.

METHOD OF SECURING TOOL-HANDLES OR THE LIKE.

SPECIFICATION forming part of Letters Patent No. 786,630, dated April 4, 1905.

Application filed July 5, 1904. Serial No. 215,418.

To all whom it may concern:

Be it known that I, ALFRED W. COCHRAN, a citizen of the United States, residing in the borough of Manhattan, in the city and county of New York and State of New York, have invented certain new and useful Improvements in Methods of Securing Tool-Handles or the Like, of which the following is a specification.

My present invention pertains to an improved method of securing tool-handles and the like; and it consists, primarily, in forcing metal in a molten or liquid condition into that portion of the handle which lies within the socket of the tool, thereby holding the tool and handle securely together. Stated in a more specific manner, the metal is caused to permeate the pores of the wood and to congeal or solidify therein, a metal which expands when cooled being preferably employed.

The invention also includes the formation of relatively small or capillary openings in the handle, which are additional or supplemental to the natural openings or pores in the wood and increase the amount of surface exposed to the action of the metal, said small openings being by preference of special form to insure the proper retention of the handle within the socket.

It will of course be understood that the invention is of general application and may be employed wherever it is desired to secure a wooden member in a socket. It may therefore be used to effect a close union between spokes and felloes or hubs, in forming joints in furniture, and the like.

For the purpose of enabling the invention to be clearly understood I have shown the same in so far as it is capable of illustration in connection with a hammer head and handle.

In the drawings, Figure 1 is a sectional view, on a somewhat enlarged scale, of a portion of a hammer head and handle, the latter being shown as impregnated with metal which has been forced into its pores and become solidified therein; Fig. 2, a similar view showing a modification of the invention; Fig. 3, a top plan view of the head and handle shown in Fig. 2; Fig. 4, a sectional view showing a still further modification, and Fig. 5 a sec-

tional view of a handle and head with a cup or vessel placed in conjunction therewith for holding the metal as it is being forced into the handle.

It will of course be understood that where the term "metal" is employed in the description and claims it is intended to cover a pure metal or an alloy or mixture of various metals, and the claims should be so construed.

In carrying out my invention the handle A, Fig. 1, is inserted into the socket (which is preferably tapered) formed in the head or tool B and a cup C, Fig. 5, so placed that the metal D therein will completely cover the projecting end of the handle. This projecting portion of the handle is subsequently removed.

The metal or alloy is melted and sufficient pressure applied thereto to force the molten metal into the pores of the handle. If metal or alloy of a sufficiently low melting-point be employed, steam under pressure may be used as the medium for melting as well as for forcing the same into the pores of the wood. In any event the pores should be expanded or opened by the application of steam to the handle or by soaking the same in hot water in order that the metal may be readily forced into said pores. A metal or alloy which expands upon cooling will, as above noted, preferably be employed, so as to more securely hold the handle in place, the expansion of the metal in the pores causing the handle to expand or to maintain its expanded condition and closely bind against the walls of the socket. The metal will likewise be forced down into the spaces or pores which are laid open upon the outside of the handle when it is formed or shaped.

It is of course conceivable that the wood may be specially treated before it is placed in the socket in such manner as to fully open or clean out the pores, removing therefrom any soluble matter—as, for instance, resin or the like—which would naturally tend to obstruct the free passage of the molten or liquid metal into the pores.

In Figs. 2 and 3 a modification of the invention is shown wherein a series of capillary or

relatively small openings E is formed in the end of the handle, the openings being connected at their inner ends by a cross opening or channel F. The metal, as in the form previously described, is forced into said openings and also into the pores at the same time. When cooled or congealed, the metal will expand and likewise cause an expansion of the handle within the socket.

10 In Fig. 4 a still further embodiment of the invention is illustrated. Inverted - wedge-shaped slots or openings G are provided, into which the metal is forced and allowed to harden.

15 It may be pointed out that when wedges are inserted into the end of the handle, as is commonly done, the friction produced in driving the same to place causes the sides of the openings formed by their passage to become 20 smooth, which in time aids in loosening the wedges, while with my invention the pressure employed forces the small particles of metal into the surfaces of the openings, which are thereby roughened, and when the metal has 25 hardened it will be found that the same is firmly secured in place.

Instead of employing the cup shown in Fig. 5 a depression may be hollowed out in the projecting end of the handle for receiving a sufficient quantity of metal, which may be heated 30 and forced into the pores of the handle, as before described, the projecting end containing the cup-shaped depression being afterward removed. It is also conceivable that the molten 35 or fluid metal might pass into the pores by gravity or, in other words, filter in.

Various other modifications of the invention will suggest themselves, which of course fall within the broad scope of the present case.

40 Other substances than metal may be employed—such, for instance, as paraffin, rosin, or the like—or, in fact, any substance which may be readily fused or melted, but which on cooling becomes comparatively firm and solid.

45 The substance should be one which will not evaporate or be injuriously affected by moisture.

Having thus described my invention, what I claim is—

1. The method of securing a wooden member in a socket, which consists in filling the pores of that portion of the member which lies within the socket with metal. 5c

2. The method of securing a wooden member in a socket, which consists in forcing fluid metal into the pores of that portion of the member which lies within the socket. 5c

3. The method of securing a wooden member in a socket, which consists in forcing fluid metal, that expands upon hardening, into the pores of the wooden member. 6c

4. The method of securing a wooden member in a socket, which consists in expanding the pores of said wooden member and forcing fluid metal into said open pores. 6c

5. The method of securing a wooden member in a socket, which consists in opening the pores of the wood and forcing fluid metal, that expands upon cooling, into said open pores. 7c

6. The method of securing handles in tool-heads or the like, which consists in opening or expanding the pores of the handle by the application of heat and forcing fluid metal into the pores thus expanded. 7c

7. The method of securing handles in tool-heads or the like, which consists in forming a series of openings in the end of the handle, subjecting said handle to the action of heat, and forcing fluid metal into the openings and pores of the handle. 7c

8. The method of securing a wooden member in a socket, which consists in filling the pores of that portion of the member which lies within the socket with a fluid or molten substance and permitting the same to cool and harden therein. 8c

In testimony whereof I have signed my name to this specification in the presence of two subscribing witnesses.

ALFRED W. COCHRAN.
